(57) **CLAIM**

The ornamental design for a wiring module, as shown and described.

DESCRIPTION

FIG. 1 is a front perspective view of a wiring module in use condition, showing my new design;

FIG. 2 is an exploded front perspective view thereof;

FIG. 3 is a front perspective view of a portion thereof;

FIG. 4 is a rear perspective view of a portion thereof; and,

FIG. 5 is a front elevation view of a portion thereof, on an enlarged scale.

The broken line showing of the environment is for illustrative purposes only and forms no part of the claimed design.
